UNITED STATES PATENT OFFICE.

GABRIEL MAROTTA, OF SEATTLE, WASHINGTON.

DESIGN FOR A STATUETTE.

Application filed September 29, 1923. Serial No. 7,367. Term of patent 3½ years.

To all whom it may concern:

Be it known that I, GABRIEL MAROTTA, a citizen of the United States, residing at Seattle, in the county of King and State of Washington, have invented a new, original, and ornamental Design for a Statuette, of which the following is a specification, reference being had to the accompanying drawings, forming a part thereof.

I claim:

The ornamental design for a statuette, as shown.

Dated September 19, 1923.

GABRIEL MAROTTA.
